UNITED STATES PATENT OFFICE.

STEPHEN D. FRY, OF ATTICA, INDIANA.

END-GATE FOR WAGONS.

SPECIFICATION forming part of Letters Patent No. 224,417, dated February 10, 1880.

Application filed December 24, 1879

To all whom it may concern:

Be it known that I, STEPHEN D. FRY, of Attica, in the county of Fountain, and in the State of Indiana, have invented certain new and useful Improvements in Dump-Gate and Scoop-Board both in one; and I do hereby declare that the following is a full, clear, and exact description thereof, reference being had to the accompanying drawings, and to the letters of reference marked thereon, making a part of this specification.

The nature of my invention consists in the construction of an end-gate for wagon-bodies, as will be hereinafter more fully set forth.

15. In the annexed drawings, Figure 1 is a longitudinal section of a wagon-body embodying my invention. Fig. 2 is a plan view, and Fig. 3 a rear elevation, of the same.

A represents a wagon-body of any suitable construction, provided with the end-gate B. This gate is provided with segmental side pieces, C C, which extend forward close to the sides on the inside of the wagon-body, and in each side piece is a curved slot, *a*. Through 25 this slot is passed from the inside a headed bolt, *b*, which also passes through the side of the wagon-body, and has a nut, *d*, screwed on the outer end. The main gate B is further provided with a smaller gate, D, hinged at its 30 upper edge, opening outward, and, when closed, fastened by hooks *h*, catching in staples *i* in recesses in the bottom of the wagon-body.

The main end-gate B may be turned rearward at an angle, as shown by dotted lines in Fig. 35 1, forming what is known as a "scoop-board" for the wagon, while the auxiliary gate D forms a dump-gate. If desired, however, the main gate may be turned upward after it has been turned down at an angle and after the hooks 40 *h* have been unhooked, so as to form a larger dump-gate.

It is evident that the slotted side pieces, C, 45 may pass on the outside of the wagon equally as well as on the inside.

Having thus fully described my invention, what I claim as new, and desire to secure by Letters Patent, is—

1. The combination, with a wagon-body, A, of the end-gate B, provided with slotted side 50 pieces, C C, the bolts *b*, and nuts *d*, substantially as and for the purposes herein set forth.

2. The end-gate B, provided with slotted side pieces, C C, and hinged gate D, in combination with the body A, bolts *b*, and hooks *h*, 55 substantially as and for the purposes herein set forth.

In testimony that I claim the foregoing I have hereunto set my hand this 26th day of November, 1879.

STEPHEN D. FRY.
